UNITED STATES PATENT OFFICE.

JACOB FOX, OF NEW YORK, N. Y.

BUTTON.

1,218,542.

Specification of Letters Patent.

Patented Mar. 6, 1917.

Application filed September 12, 1916. Serial No. 119,720.

To all whom it may concern:

Be it known that I, JACOB FOX, a citizen of the United States, residing at New York, in the county of New York and State of New York, have invented certain new and useful Improvements in Buttons, of which the following is a specification.

This invention relates to apparel buttons and has as its object to provide a novel form 10 of celluloid or composition button of that type which are provided with what is commercially known as dapped backs and it is one object of the invention to provide a button which may be manufactured at little 15 expense and which will be substantial and also attractive in appearance.

From the accompanying drawings,

Figure 1 is a perspective view of the improved completed button embodying the 20 present invention,

Fig. 2 is a vertical front to rear sectional view therethrough, and

Fig. 3 is a perspective view of the back before application of the facing member 25 thereto.

In the drawings, the numeral 1 indicates in general the back of the button and this back is preferably formed from celluloid although any other similar material may be 30 employed for the purpose if found expedient and the said back is in the nature of a hollow shell open at its forward side, as indicated at 2, the rear side of the said shell being provided with the usual perforations 35 3 for the passage of the thread for securing the button to a garment. From a point adjacent its forward side, the shell is continuously curved inwardly as at 14 so that the open front of the button is of a diameter 40 slightly less than the maximum diameter of the shell and while the button is here illustrated as substantially conoidal in form, it will be understood that it may be polygonal or oval in shape or in fact, may assume any 45 shape desired. The open front of the back is defined by an edge 5 which, in the manufacture of the back, may be more or less rough and uneven as the said edge in the completed button is completely obscured as 50 will presently be made apparent.

The numeral 6 indicates a facing for the back which facing when united with the back completes the button and this facing in the present instance, is annular in form and exteriorly, of a diameter to have its 55 periphery register with the outer line of the edge 5 so that when the facing is assembled with the back and united to the said edge, the edge will be completely concealed. The edge 5, moreover, is of a width 60 less than the distance between the inner and outer edges of the facing member 6 so that the said facing member, at its inner edge portion, will project inwardly beyond or overhang the said edge 5. The facing member 65 may assume various designs and shapes depending upon the fancy of the manufacturer and upon the general contour of the open front of the back 1.

From the foregoing description of the invention, it will be understood that a button constructed in accordance with the principles thereof may be manufactured at a very low cost and yet the button will be 70 very substantial and may be as plain or as 75 ornamental in its appearance as the fancy of the manufacturer may dictate.

Having thus described the invention, what is claimed as new is:

1. A button having a back in the form 80 of a shell open at one side and provided at its opposite side with thread perforations, and a facing member secured to the edge of the button at the open side thereof and having an opening located opposite the said 85 perforations.

2. A button having a back in the form of a shell open at one side and provided at its opposite side with thread perforations, and a facing member secured to the edge of the 90 back at the open side thereof, the said facing member concealing the said edge and having an outer marginal contour substantially the same as the outline of the said edge, the facing member having an open 95 middle portion located opposite the said thread perforations.

In testimony whereof I affix my signature.

JACOB FOX. [L. S.]
